UNITED STATES PATENT OFFICE

MARCUS H. RHODES, OF UNIVERSITY CITY, MISSOURI

SWITCH

Application filed September 6, 1929. Serial No. 390,689.

This invention relates to electric switches, and with regard to certain more specific features, to timed, delayed action switches.

Among the several objects of the invention may be noted the provision of an electric switch having improved means for effecting a higher speed of circuit making and breaking; the provision of a switch having a delayed action subsequent to actuation thereof, there being provided controllable means for varying by increments the time of delay; the provision of a switch of the class described in which one of said increments is of a different quantum than the others; the provision of a switch of the class described which may have the timed delay feature temporarily thrown out of operation to permit non-delay action; the provision of a device of the class described which merely by eliminating parts and without substantial additions or re-designing may be changed to function according to a different timing; and the provision of a switch of the class described which shall be of maximum simplicity and ruggedness and which shall be adapted to operate in all positions thereof and under all circumstances to positively start timing action.

Other objects will be in part obvious and in part pointed out hereinafter.

The invention accordingly comprises the elements and combination of elements, features of construction, and arrangements of parts, which will be exemplified in the structure hereinafter described, and the scope of the application of which will be indicated in the following claims.

In the accompanying drawings, in which are illustrated several of the various possible embodiments of the invention:

Fig. 1 is a plan view of a switch embodying the invention, the same being shown as set for time delayed, circuit breaking action;

Fig. 2 is a vertical, longitudinal section taken on line 2—2 of Fig. 1, a gear supporting plate being shown as removed;

Fig. 3 is a vertical longitudinal section taken on line 3—3 of Fig. 1;

Fig. 4 is a cross section taken on line

4—4 of Fig. 1, certain parts having been removed for clarity;

Fig. 5 is a developed view showing a gear train and connected parts such as used in one form of the invention, the development being defined and taken along line 5—5 of Fig. 2;

Fig. 6 is a longitudinal section similar to Fig. 2 but on a reduced scale, showing a second form of the invention;

Fig. 7 is a view similar to Fig. 6 showing a third form of the invention;

Fig. 8 is a detail elevation showing a main gear;

Fig. 9 is a detail showing a main spring pawl; and,

Fig. 10 is a plan view of a pawl.

Similar reference characters indicate corresponding parts throughout the several views of the drawings.

Referring now more particularly to Fig. 1, there is illustrated at numeral 10 a cover plate fastened down by two cover plate screws 53 to a lower U-shaped plate 1 (see Fig. 4 for the U-shape of plate 1). The cover plate 10 is provided with openings 56 and 57, the former for accommodating an oscillatory timing control handle or lever 8 and the latter for accommodating an oscillatory switching or circuit control lever 3, both levers extending outwardly through the openings 56, 57 from the inside of the switch. The function of the switching lever 3 is to make and break the circuit and also to be manipulated or actuated for varying the time of current flow after the switch lever 3 has been set to "off" position; and the purpose of the time lever 8 is to set the switch either for timed or non-timed operation. The opening 56 is provided with a bight 58 for displaying one portion of the periphery of a time indicator wheel 35, also located within the switch.

The cover plate screws 53 hold the cover 10 to said U-plate 1 (see Fig. 2) and U-plate screws 51 hold the said U-plate 1 to a porcelain box 25 (see Fig. 3). This box 25 forms an insulating housing for the switch parts. Pole pieces or line terminals 5 and 6 are supported therein, said pieces carrying contact 100

screws 50 for fastening line wires or the like. Stationary knife blade extensions 59 and 60 depend from the poles 5 and 6 respectively for engagement by and with pairs 5 of upwardly extending spring contactors or terminal engaging elements 11, said contactors 11 being formed integrally with a connecting bar 61, the latter being fastened with rivets 29 to a fibre contactor slide 24. The 10 slide 24 slidably rests upon guides 62 formed integrally with the bottom of the porcelain box 25. It will be recognized that when the contactor 11, 24, 61 is in the position shown in Fig. 3 that it is in circuit closing position 15 with respect to the poles 5, 6. When the contactor is moved to the left the circuit is open, because the contactors 11 disengage from the blades 59, 60. In order to facilitate contacting, the extensions 59, 60 are somewhat 20 sharpened as indicated at numeral 63 for ready engagement with flared ears 64 of the pairs of spring contactors 11. Operation of the contactors 11 is effected by forming an opening 65 next to the off-set connecting bar 25 61 and through the fibre slider 24. This opening is substantially rectangular in shape. Coordinating with and within this opening 65 is a depending tongue 66 of a switch hammer 4, said hammer 4 being adapted to swing 30 on gudgeons 67 extending from portions of the U-plate 1 (see Fig. 4). It will be noted that the switch hammer can swing freely through a substantial arc of approximately twenty-five degrees before striking the ends 35 of the opening 65, thus providing a lost-motion engagement.

The switch hammer 4 is provided with a spring-seating extension 68 for receiving a switch spring 45, the spring being shown in 40 Fig. 3 but omitted in Fig. 4 for purposes of clarity. The spring 45 extends upwardly and reaches against the lower rounded end 69 of a switch lever 3, the latter being swung on a switch lever pin 28 fastened between the 45 sides of the U-plate 1. It will be seen thus far that the switch hammer 4, switch lever 3 and reacting switch spring 45 form an over-centering, toggle linkage. The action of this linkage is such that when the upper re- 50 action point 93 of the spring at the rounded end 69 crosses the center line CL of the switch hammer, for instance, to the right, then the spring is put under compression and tends to throw the switch hammer to the left, pro- 55 vided there is no other mechanism to prevent it. For example, in Fig. 3 the spring is in compressed reacting position for throwing the switch hammer sharply in a clockwise direc- 60 tion to the left, whereupon the tongue 66 will gain momentum in passing through its lost-motion path in the opening 65. Then the tongue 66 strikes the left-hand end of the opening 65 with a sharp blow and instantly 65 throws the contactors 11 out of engagement

with the extension of the poles 5, 6. It should however be noted that another part of the mechanism, which will be described, normally prevents this action from the Fig. 3 position until a predetermined release is effected. These features will be described 70 hereinafter.

Continuing the reference to the toggle action, it will be noted that if the switch lever is thrown to its opposite, right hand extreme 75 (Fig. 3), then the point 93 will pass over said center line CL which will at that time be in the open switch position to the left. This passage over the center line throws the spring reaction into an over-centering relationship, such that the switch hammer is suddenly forced to assume a counter-clockwise movement. The tongue 66 travels with loss of motion in the reverse direction through the opening 65 and strikes the right hand 80 thereof with a sudden blow, thereby quickly snapping the switch shut, the contactors 11 moving to the right into engagement with extensions of the poles 5, 6. It is to be noted that when the switch lever 3 is thrown for 85 closing the switch, that the switch closes immediately, there being no delaying action in the mechanism such as will be explained in connection with opening the switch from the closed position. In this connection, it 90 will be noted that Fig. 3 shows the toggle linkage in such position that the spring is compressed and over-centered and ready to throw the switch hammer so as to open the switch, but there is a temporary mechanical 95 restraint which will now be described.

The parts above described are in one compartment of the box 25. This compartment is defined by the right side of the box (Fig. 4) part of the bottom thereof, including the 105 guides 62 and one side 70 of the U-plate 1 (see the right hand portion of Fig. 4). The other compartment is defined by the left wall of the box 25 (Fig. 4), the remainder of the bottom of the box and by a flat plate 2 which 110 by means of plate spacers 26 is spacedly mounted with respect to one wall 70 of the U-plate 1 (see the left hand side of Fig. 2 and Fig. 4). An arcuate opening 71 in the wall 70 of the U-plate 1 accommodates an 115 extension ear 72 of the switch hammer 4. The function of this extension is to be held and released for delaying purposes. The coordinating latching apparatus therefor will be described hereinafter.

Pivoted to the switch lever 3 by means of a rivet 37 is a pawl 7 which has an ear 73 provided for fastening a pawl spring 46 which reacts from the switch pin 28 to hold an oppositely extending ear 74 in engagement with the teeth of a ratchet wheel 18 located in said left hand compartment (for clarity, the spring 46 is shown in Fig. 3 but not in Fig. 4). The ear 74 is pulled into engagement with the teeth of said ratchet 18 when- 120 125 130

ever lever 3 is thrown into its "on" position and in the "off" position of the lever 3 said pawl ear 74 is drawn up against the side of an opening 71-S, as illustrated in Fig. 2, so as to permit clearing of the ratchet teeth by the ear 74 when it is desired to return the ratchet teeth according to the functions hereinafter set out. As will be made clear, the advance of the ratchet is one tooth every time the switch lever is thrown to "on" position. In other words, when the lever 3 moves from "off" to "on" position, the pawl 74 rides down the left face of the opening 71-S and engages a tooth such as X (Fig. 2) for advancement through an arc corresponding to the arc occupied by one ratchet tooth. The switch lever may be serially or repeatedly operated to advance the ratchet step by step.

20 The ratchet 18 (Fig. 4) is integrally movable with a main spring hub 30 and also with a main spring pawl wheel 13 so that the ratchet 18, hub 30 and main spring pawl 13 may turn together. On the other hand, 25 there is provided a main gear wheel 19 which is relatively rotatable with respect to said parts 13, 18, 30.

A detail plan of the gear wheel 19 is shown in Fig. 8 and a detail plan of the main spring 30 pawl 13 is shown in Fig. 9. Examination of the Figs. 8 and 9 shows that the gear 19 is provided with openings 76 with which are matched by detents 77 of pawl 13, a plurality of which detents are used. The detents 35 77 are formed in such a direction and engage such gear openings 76 in such a manner that when the operation of lever 3 results in movement of the ratchet 18, return of said ratchet under action of spring 44 is prevented by the 40 engagement of the side detents 77 with certain of the gear wheel openings 76. The gear wheel resists return action of the ratchet 18 caused by the initially provided tension in the main spring 44, because the gear train 45 into which it is connected is at this time locked against movement.

The timing gear train referred to in the paragraph above is shown more particularly in Fig. 5 wherein the gear 19 is shown as 50 meshing with a pinion 21. Said pinion 21 is integrally rotatable with a gear 20 which meshes with a second pinion 32. A second gear wheel 20-A is integrally movable with the pinion 32 and meshes with a third pinion 55 33 the latter being made fast with a third gear wheel 20-B. This last wheel 20-B meshes with a pinion 78 which is integrally movable with an escapement wheel 22. The escapement wheel 22 is controlled by a vibrating anchor escapement piece or pallet 14 pivoted at 79 and provided with pallet pins 43 which, as the pallet vibrates, permit intermittent escaping action of the escapement wheel 22. Vibration of the pallet is effected 65 by the action of a hair spring 80 and asso-

ciated balance wheel 23, the latter having a pin 81 cooperating with a slotted extension 82 of the pallet 14.

It will be apparent from the above that the escapement will permit the gear train to run down under action of the main spring 44 only at a predetermined rate. It has also been made clear above that when the switch handle 3 is operated to its "on" position that the ratchet 18 is picked up by the pawl 74 to be moved through the angle subtended by one pawl tooth. This means that the main spring pawl 13 is moved the same angle and it is desirable at this time that the gear train be locked. In order to accomplish locking there is pivoted near the escapement extension 82 what I choose to call bell crank flexor which is drawn counter-clockwise by the reaction of a tension spring 48 so that normally the lower extending leg thereof engages said pallet extension 82 to throw the same counter-clockwise to the right, thereby locking the escapement wheel 22 and also locking the gear train. It is clear that under these conditions the ratchet 18 can be operated with the main spring pawl 13 without effecting gear train movement, that is to say, the lever 3 may be thrown from "off" to "on" position without effecting gear train movement, the pawl piece 13 ratcheting in the openings 76 of the main gear 19.

On the other hand, when the switch handle 3 is thrown from "on" to "off" position it is desirable, for reasons which will be stated, that the escapement be released so that the gear train may run down a predetermined amount. In order to accomplish this there is provided the upper leg of said bell crank flexor 12 which is adapted to be engaged by an extending portion 83 on the switch handle which turns the bell crank 12 clockwise to the position illustrated in Fig. 2 in which the pallet 14 may vibrate under the controlling action of said hair spring 80 and balance wheel 23.

One of the excellent features of this flexor construction is that when the switch handle 3 is in its "on" position, the flexor 12 throws the extension 82 off the line of centers between the escapement wheel center and the balance wheel center. Thus when the switch is brought to its "off" position there is never any chance that the escapement pallet will be on dead center, such as is the case with watches and clocks which often require to be shaken to start them after they have run down.

The flexor has two purposes, namely, to act as a starter, preventing dead centering and to prevent the escapement from operating until the switch lever has been returned to rest at its "off" position. Otherwise the escapement would operate to permit running down of the time delay mechanism while the switch lever rested at the "on" position. Fig. 130

2 shows how the flexor is provided with an offset 94 reaching through an opening 95 in the plate 70 for reacting contact with the switch lever 3.

5 In the present embodiment the ratchet 18 has ten thirty degree teeth and one sixty degree tooth. The gear 19 has 12 openings corresponding to twelve angular divisions so that each time a single movement from "off" to "on" of the switch handle 3 is effected, there will be normally an advance of thirty degrees of the ratchet and main spring pawl 13, the pawl during advance strokes moving its detents from one opening to the next successive opening in gear 19. The gear at this time does not move for the reasons given above.

20 The main spring pawl 13 is also provided with a lug 84, which as the switch handle 3 is moved to "on" position is retracted in a clockwise direction (Fig. 2) through a thirty degree arc for every "on" movement of the handle 3. If the handle is moved to "on" position once, then a thirty degree retraction 25 is effected and if it is moved twice a sixty degree retraction is made and so on. The purpose of the lug 84 is to serve as a release for latching parts which it was said above would be described in connection with the holding of the switch hammer in its Fig. 3 position against the compressive action of the spring 45. This mechanism will be described now.

30 It comprises a latch cam 9 pivoted at 85. This cam has a leftward extension 86 (Fig. 2) having a claw 87 which is adapted to hook in under the ear 72 when said ear, by actuation of the switch lever 3 to its "off" position, is thrown into its Fig. 2 position. A 35 sloping face 88 on the claw permits the ear 72 to readily thrust it aside against the reaction of a time lever spring 47. The time lever spring 47 reaches from a lug 89 to one arm 90 of a bell crank lever 91 in connection with 40 which is the time lever 8 extending to the outside of the switch. The reaction points of the time lever spring 47 are so arranged that when the time lever 8 is thrown to its extreme positions, "on" and "off", there is an over-centering action which throws the latch cam 9 45 into and out of locking position. When the time lever is in its "on" position (Figs. 1 and 2) the latch cam is ready to lock the ear 72 back whenever the switch lever 3 is thrown 50 into "on" position to throw the hammer 4 to the right as shown in Fig. 3. Whenever the time lever is in its "off" position there will be no latching or locking action by the latch cam and throwing of the switch lever 3 from 55 "on" to "off" position results in immediately breaking the circuit instead of a delayed breaking being effected. It will be noted that the bell crank lever 91 for the time lever 60 65 8 is rotatably mounted on the hub member 30 (see Fig. 4).

Another feature of the sloping face 88 of the latch cam 9 is that it is adapted to be engaged by the main spring pawl 13 as said pawl returns under action of the main spring 44 on the gear train, said train being controlled by the escapement. It will be noted that for all increments of time added by throwing the switch lever 3 are equal, that is, subsequently to the first switch lever throw. That is to say, the pawl 13 moves through equal distances from its retracted position, and opening action of the switch, as the timing train runs down, is delayed proportionally to the time that it takes the pawl 13 to reach the latch cam 9. However, the interval caused by the first throw of switch lever 3 is that one in which the pawl 13 is approaching sloping face 88 of the latch cam 9. Inasmuch as this face slopes outwardly to the pawl 13 the last interval of time is shortened, because the latch cam 9 will release the ear 72 before the pawl 13 is moved through the full thirty degree arc. The advantage of this is that if it is desired to throw the switch to "off" position and merely walk out of the room or the like, the first delayed action will be relatively short. If it is desired to set the switch for a longer time such as until a reader falls asleep or the like, then the switch lever 3 may be operated two or more times and a proportionately longer time delay will be effected.

60 In Fig. 2 it will be noted that one of the teeth of the ratchet subtends twice the amount of arc that the others do. The reason for this is that if the switch handle 3 is operated eleven times to set the switch for maximum time delay, it is undesirable that an operator be permitted to continue abnormally winding up the device by operating the switch handle 3. The long tooth Y prevents this because the actuating stroke of the lug 74 is not great enough to catch back on the next first tooth. Thus, the device is fool-proof.

65 The operation is as follows:

70 Assuming that the switch lever 3 and the time lever 8 are both in "off" positions, an operator may then throw the switch lever 3 to an "on" position and effect an instantaneous closure of the switch or to an "off" position again with immediate and instantaneous operation, that is, it operates not unlike the ordinary toggle switch. The reason for this is that when the time lever 8 is in "off" position (to the right Fig. 2), then the time lever 75 80 spring 47 is over centered so that the latch cam 9 is moved counter-clockwise and does not latch the ear 72. Even under this mode of operation, however, the present switch has novelty, in that the lost-motion engagement between the hammer 4 and the contactor slice 24 results in an exceedingly quick making and breaking of the circuit.

75 80 85 90 95 100 105 110 115 120 125 130 Whenever it is desirable to operate the switch with the time-delay feature, it is only

necessary to throw the time lever 8 to its "on" position (see Figs. 1 and 2). This results in the time lever spring 47 being over centered so as to force the latch cam 9 clockwise so that upon subsequently throwing the switch lever 3 to an "off" position the ear 72 will spring behind the claw 87 and be caught so that upon subsequently turning the switch lever 3 to an "on" position the ear 72 will be held and hence also the hammer 4. Subsequently upon throwing of the switch handle 3 to an "off" position the toggle linkage shown in Fig. 3 will be held in circuit closing position until the gear train runs down under action of the main spring 44 and the control 10 of the escapement mechanism. It will be appreciated that the movement of the switch handle 3 to "on" position resulted in the lug 74 moving the ratchet up one step and that 15 at the same time the gear train was locked by the interfering action of the released flexor 12 on the escapement, said flexor having been released to interfere by moving the switch handle 3 part 83 to "on" position. 20 The return of the switch handle 3 to "off" position removes the interference of the flexor 12 from the escapement mechanism and permits the gear train to run down and the pawl 13 to return so as to effect movement of the 25 latch cam 9 to release the ear 72, whereupon the overcentered compressed spring 45 snaps the switch handle 4 to move the slider 24 and open the circuit.

As above described, for one cyclic movement of the switch handle 3 from "off" to "on" to "off" position results in a comparatively short time delay, because of the advanced contact with the pawl 13 effected by the sloping surface 88 of the cam 9. It will be noted that when the switch lever 3 is thrown on, that the main spring pawl member 13 rides over the then locked main gear 19 (gear 19 is in the then locked train) and the detents 77 catch in the next set of openings of 40 the main gear for subsequent return therewith. The ratchet wheel 18 can return because when the switch lever 3 is in "off" position the lug 74 had ridden up the face of said opening 71 so as to clear the ratchet 45 teeth.

If the optimum time delay is desired, the operator after having set the time lever 8 to "on" position strokes the switch lever 3 to "on" position enough times to provide the 50 total amount of time delay desired. For instance, the first stroke may provide a time delay of only one-half minute or so, due to the action of the face 88. Thereafter each stroke cumulatively adds time delay in proportion to the number of strokes effected. For instance, five minutes may be added per stroke, if each ratchet tooth provides arc enough that it takes the pawl five minutes to traverse the same with the particular escapement and gear train used.

One of the features of this cumulative action is that after the switch has once been turned on, subsequent stroking of the switch lever 3 does not result in the circuit being reopened, because it is locked shut by the latch cam 9 on the first stroke. The circuit is ready to spring open under action of toggle linkage (Fig. 3) whenever the switch handle 3 is turned off, whereby the flexor 12 is released and consequently the escapement and gear train. The lug 84 then returns to effect opening of the switch at a predetermined time by throwing aside the latch cam 9.

Whenever it is desired to temporarily return to non-delay action this may be done by 70 setting the time lever 8 to "off" position, before, after or during operation of the handle 3.

Another advantage of this construction can be gleaned by examination of Figs. 2, 6 and 7. In Fig. 2 a triple geared train is used. This results in a greater gear reduction from the escapement to the main gear and attached main spring pawl 13. Thus a long time delay switch is effected. If it is desired to shorten the time delay, the gear member comprising gear 20—A and pinion 32 may be removed and gear member comprising gear 20 and pinion 21 replaced on its center line. The centers of these two gear members are equally distant from the center of the main gear 19. The reason that the gear member 20, 21 is retained is that its pinion element is a coarser pitch for engagement with the coarser pitch of the main gear 19 while the gear element thereof has the same pitch as the removed gear and will mesh with the pinion 33 with which said removed gear meshed. With this removal, all other parts being the same as they were, there is effected a proportionally shorter time delay throughout the action of the switch. The modified form is shown in Fig. 6.

In Fig. 7 is shown a modification wherein two wheels in the train had been removed and the right hand gear pinion of Fig. 2 mounted on the extreme left of the train (Fig. 7). In making this change a new center needs to be located for the last axis, because the last axis in Fig. 2 is not at the same distance from the center of the main gear as the axes of the other parts of the train.

For the convenience of an operator, there is provided on the end of the shaft 55 which is fixed to the ratchet, a time indicator wheel 35 which fits into an opening 92 in the porcelain box and which may be viewed at its periphery through the bight 58 of the cover 10, referred to in connection with Fig. 5. The periphery of this indicator wheel is provided with suitable indicia representing the time that it will take for the switch to run down to an "off" position. Clearly, the indicia advances into registry with the bight 58 as the ratchet is advanced under the manipulation of the switch lever 3 to "on" and "off" posi-

tions. As the gear train runs down prior to automatically turning the switch off the time indicator wheel returns with it to zero indication. The last scale reading near zero on the indicator is shorter than the others, because of the shorter increment of time consumed for the first switch actuation, already described.

It is to be understood that the switch described is for application to circuits which are adapted to be turned "off" after a time delay. It is perfectly clear that the time may be reversed so that the time delay action is effective to close the circuit after a predetermined time. This could readily be done by making the contactor move into circuit closing position after the time delay action, instead of into circuit opening position as it does now.

Another advantage of this system over previous ones is that the timing mechanism does not operate the switch per se, but merely controls it according to mechanical relay principles. The timing mechanism has very little strain on it because of the gear reduction from the escapement to the main gear. The great length of the claw arm 86 of the latch cam provided high leverage against the action of the spring 47 and thus reduces the forces required of the timing mechanism for switch opening purposes.

Another advantage is that the timing mechanism can be made small and does not add much volume to the switch because it does not operate the switch but merely controls it. The main spring 44 which stores energy from the manual operation of the operator does not feed it energy through the timing gears.

Another advantage is that the electrical elements per se are in a separate and isolated chamber and that the escapement mechanism is in another chamber, all elements being enclosed in porcelain. Hence the switch is fire-proof. It is to be understood that the timing mechanism needs not be wound up from time to time because initial tension is put into the main spring and actuation of the switch lever merely winds it up tighter after which it again runs down when delayed action is effected. The spring runs down to its initial tension condition.

It will be seen that if an operator should have the time lever in "on" position and serially operate the switch lever that he could leave said switch lever in the "on" position and the lights or the like controlled from said position would continue burning without the time delay period being reduced, unless the switch handle is turned "off." When the switch handle is turned "off" the time delay periods starts to become reduced as the gear train runs down to a point where the pawl 13 will trip out the latch cam 9, to permit the toggle circuit opening action.

It will be clear that if an operator should

set the switch for an extended delayed action and change his mind and desire to open the circuit immediately, this could readily be done by moving the time lever to "off" position. This (see Fig. 2) results in tripping the latch cam 9 and freeing the lug 72 so that upon setting the switch lever 3 to open position, if it is not already in such position, the switch will immediately open. If the switch lever is in "off" position when the time lever 8 is moved to "off" position the switch immediately breaks the circuit.

Opening of the circuit by setting the time lever to "off" position while the switch lever is in "off" position does not affect the operation of the timing train. Hence, if the time delay had been set for one-half hour and then the switch immediately opened by setting both time and switch levers to "off" positions, the timing train would continue to run while the circuit is open (for instance, after the lights are out); then, if fifteen minutes later the switch were again turned on by means of the switch lever there would still remain fifteen minutes of time delay action available. However, an operator would be aware of this because the indicator 35 would show it.

It will be noted that after the time lever 8 has been snapped to "off" position, thereby eliminating the time delay operation, still the switch lever 3 operates the time movement, thus preventing the movement from becoming gummed with oil, dust and lint or the like, and causing it more likely to remain in operable condition.

Likewise should the gear train "freeze" with foreign material, an operation of lever 3 would build up force in the main spring 44 to eventually force the "freeze." It will further be noted that upon operation of the switch once per day, the operator would, unconsciously, add power which in the end would probably break the "freeze" so that the operator finding the switch apparently out of order might find it back in order after a few reciprocations of lever 3.

In view of the above, it will be seen that the several objects of the invention are achieved and other advantageous results attained.

As many changes could be made in carrying out the above constructions without departing from the scope of the invention, it is intended that all matter contained in the above description or shown in the accompanying drawings shall be interpreted as illustrative and not in a limiting sense.

I claim:

1. A time delay switch comprising a circuit controlling handle and a timing control handle, means for closing and opening a circuit from said circuit controlling handle operable instantaneously when the time control handle is in one position and operable by delayed action when the time control handle is in an-

- other position and means for effecting variation in the time delay by repeatedly manipulating the circuit controlling handle to closed circuit position from open circuit position.
2. A time delay switch comprising a circuit controlling handle and a timing control handle, means for closing and opening a circuit from said circuit controlling handle operable instantaneously when the time control handle is in one position and operable by delayed action when the time control handle is in another position, means for effecting variation in the time delay by serially manipulating the circuit controlling handle to closed circuit position from open circuit position and means for preventing opening of the circuit during said serial operation.
3. A time delay switch comprising a circuit controlling handle and a timing control handle, means for closing and opening a circuit from said circuit controlling handle operable instantaneously when the time control handle is in one position and operable by delayed action when the time control handle is in another position, and means for controlling the time of delay by repeated operation of the circuit controlling handle when the time control handle is in said other position.
4. A time delay switch comprising line terminals, a terminal engaging element, means for actuating the terminal engaging element to connect and disconnect the terminals, said actuating means effecting immediate connecting action of the engaging element and time delay disconnecting action of said engaging element and means for changing the duration of the time delay actuated by repeating the connecting and disconnecting actuation of the said actuating means.
5. A switch comprising line terminals, a movable engaging element, a switch lever, means for controlling movement of the engaging element from said switch lever to make and break contact with the line terminals, said lever having a spring winding position in its circuit making position, means for delaying the contact controlling function of the switch handle at the time of one of the switch controlling actions comprising a latch, means for releasing said latch driven from a spring, means controlled by repeating operation of the switch handle to increase the tension of the spring and to retract the latch releasing means, automatic means for preventing unwinding of said spring to cause release of the latch and means for releasing said automatic means when the switch lever is retracted from its spring winding position.
6. A switch comprising line terminals, a movable engaging element, a switch lever, means for controlling movement of the engaging element from said switch lever to make and break contact with the line terminals, means for delaying the contact controlling function of the switch handle at the time of
- one of the switch controlling actions comprising a latch, means for releasing said latch driven from a spring, means controlled by repeating operation of the switch handle to increase the tension of the spring and to retract the latch releasing means, automatic means for preventing unwinding of said spring to cause release of the latch and means for releasing said automatic means when the switch lever is retracted from its spring winding position.
7. A timed switch including circuit making and breaking means, an oscillatory handle controlling said means, means for delaying switch action when the handle is thrown to one extreme, means for proportionally increasing the delayed action by repeating oscillations of the handle and means for throwing the delay actuating means into operation when the handle is thrown to its opposite extreme.
8. A timed switch including circuit making and breaking means, an oscillatory handle controlling said means, means for delaying switch action when the handle is thrown to one extreme, means for proportionally increasing the delayed action by repeating oscillations of the handle and means for throwing the delay actuating means into operation when the handle is thrown to its opposite extreme, said last-named means including an element operable to positively insure starting of the time delayed action when it is required and locking the same against operation when it is not required.
9. A switch comprising line terminals, a terminal engaging element, a switch handle for making and breaking contact between said engaging element and line terminals, timed means for controlling the period of delay, means for delaying subsequent switch opening when the switch is closed, means for increasing said delay by repeating closure action of the handle, the opening repetition action subsequent to the first closure action being prevented from opening the circuit until said timed means causes opening thereof.
10. In a time delay switch, circuit making and breaking means, a switch lever for operating said means, a latch for temporarily holding the circuit making and breaking means in a predetermined position, latch releasing means adapted to be retracted from the latch a distance which is a function of the number of times the switch lever is operated, a timing mechanism adapted to return the latch releasing means to move the latch whereby the latter releases the switching means, the time consumed in said return being determined by the distance traveled.
11. In a time delay switch, circuit making and breaking means, a switch lever for

operating said means, a latch for temporarily holding the circuit making and breaking means in a predetermined position, latch releasing means adapted to be retracted by increments a distance determined by the 5 number of times the switch lever is operated, a timing mechanism adapted to return the latch releasing means to move the latch whereby the latter releases the switching means, the time consumed in said return being 10 determined by the distance traveled.

12. A timed switch including circuit making and breaking means, an oscillatory handle controlling said means, means for delaying switch action when the handle is thrown to 15 one extreme, means for proportionally increasing the delayed action by repeating oscillations of the handle and means for throwing the delay actuating means into operation 20 when the handle is thrown to its opposite extreme, said last-named means including an element operable to positively insure starting of the time delayed action when it is required.

13. A timed switch including circuit making and breaking means, an oscillatory handle controlling said means, means for delaying switch action when the handle is thrown to one extreme, means for proportionally increasing the delayed action by repeating oscillations of the handle and means for throwing the delay actuating means into operation when the handle is thrown to its opposite 30 extreme, said last-named means including an element operable to lock the time delaying action when it is not required.

14. In a time delay switch, circuit making and breaking means, a switch lever for operating said means, a latch for temporarily holding the circuit making and breaking 40 means in a predetermined position, latch releasing means adapted to be retracted by increments a distance determined by the number of times the switch lever is operated, a timing mechanism adapted to return the latch 45 releasing means to move the latch whereby the latter releases the switching means, the time consumed in said return being determined by the distance traveled and means 50 providing delayed action when the switch is operated once, said last-named delayed action being less than subsequent increases in delay.

In testimony whereof, I have signed my 55 name to this specification this 29th day of August, 1929.

MARCUS HALL RHODES.
